(57) **CLAIM**

The ornamented design for an adjustable container cutting die, as shown and described.

DESCRIPTION

FIG. 1 is a top right perspective view of the first embodiment of the cutting die of the present invention.

FIG. 2 is a top right perspective view of a second embodiment of the cutting die of present invention.

FIG. 3 is a top right perspective view of a third embodiment of the cutting die of the present invention.

FIG. 4 is a top right perspective view of a fourth embodiment of the cutting die of the present invention.

FIG. 1A is a side view of the first embodiment of the cutting die of the present invention.

FIG. 2A is a side view of the second embodiment of the cutting die of the present invention.

FIG. 3A is a side view of the third embodiment of the cutting die of the present invention.

FIG. 4A is a side view of the fourth embodiment of the cutting die of the present invention.

FIG. 5 is a side view of the first, second, third and fourth embodiments of the cutting die of the present invention; and, FIG. 6 is a side view of a fifth embodiment of the cutting die of the present invention.

Elements depicted by broken lines are mountings and are not claimed as part of the invention.

The back of the cutting die is a blank and unornamented and is not claimed herein.
